CENTRALIZED TRAFFIC CONTROLLING
SYSTEM FOR RAILROADSFrederick W. Brixner, Gates, N. Y., assignor to
General Railway Signal Company, Rochester,
N. Y.

Application December 30, 1936, Serial No. 118,337

7 Claims. (Cl. 177—353)

This invention relates to centralized traffic controlling system for railroads, and it more particularly pertains to the communication part of such systems.

5 The present invention contemplates a centralized traffic controlling system in which communication is established between a control office and a large number of outlying field stations by means of a communication system of the two-wire selective coded simplex type. The switches and signals at a plurality of stations located along the railroad track are controlled from the control office by the coded impulses applied to the two-wire line circuit.

10 15 The switches and signals are under the supervision of the operator at the control office so that the condition of such switches, signals and various other traffic controlling devices at the distant stations will be transmitted to the control office for providing the operator with the necessary information for governing train movements. In a system of this type, a series of impulses forming a particular code combination is transmitted over the line circuit for the selection of a particular field station and the transmission of controls to the selected station.

20 25 Similarly, a series of impulses forming a particular code combination is transmitted over the line circuit for the registration of a field station in the control office and the transmission of indications from the sending station. The control and indication circuits are so interrelated in the system that controls and indications are transmitted on separate cycles of operation, in other words, the system is of the simplex type. Since the present invention is more particularly directed to outbound code transmission, that is, the transmission of control codes, and since numerous forms of indication transmission may be used in the present system, the drawings and the description will be limited to the control functions of a centralized traffic controlling system.

30 35 The circuits are so organized, that, during a control cycle, the control office acts as the driver of the system, placing the proper polarity from a control office line battery on the line circuit and creating long and short energized and de-energized portions at each step of the system, as required to select a station and to control the 40 45 functions at the selected station. The early polar impulses are used for station selection and it therefore becomes necessary to store up the function control impulses which are sent out during the early energized and deenergized portions of the first steps until the end of the cycle, at which

time they will be executed, provided the station has been selected during this cycle.

5 In the present system, polar impulses are used for station selection, that is, each energization of the line is positive or negative. For function control the capacity of the system is increased by making the energized period of a step either long or short, thus giving a choice of two for each energized period and the deenergized period for each step is made either long or short, thus giving a 10 15 choice of two more for each step. These four combinations, plus the choice of two provided by the positive or negative line energization for each step, gives a total capacity of six code combinations for each step of the system.

20 25 The polarity of the impulses during the transmission of controls is determined in the control office by reversibly connecting the line battery to the line circuit. The control office acts as the driver or the impulser, and makes the impulse or energized portion of the impulses either long or short, as well as making the deenergized or time space portion of the impulses either long or short.

30 35 The above mentioned characteristic features and additional features of the present invention will be explained more in detail in the following description and various advantages of the invention will be in part pointed out and in part apparent as the description progresses.

40 45 In describing the invention in detail reference will be made to the accompanying drawings which illustrate one method of carrying out the invention by way of example. The drawings illustrate, in a diagrammatic manner, the apparatus and circuits employed and for convenience in describing the invention in detail those parts having similar features and functions are designated in the various views by like letter reference characters, generally made distinctive either by reason of distinctive exponents representative of their location in the system or by reason of distinctive preceding numerals representative of the order of their operation and in which:—

50 55 Figs. 1A and 1B placed end to end in the order named and with correspondingly numbered lines in alignment, illustrate in schematic form the apparatus and circuit arrangements employed at a typical control office embodying the present invention.

Figs. 2A and 2B placed end to end in the order named and with correspondingly numbered lines in alignment, illustrate the apparatus and circuit arrangement employed at a typical field station embodying the present invention.

The illustrations in the drawings are schematic

and abbreviated for the purpose of clearness and simplicity. In following the detailed operation of the system for the transmission of controls, Fig. 2A should be placed to the right of Fig. 1B with the line and return conductors in alignment.

The arrangement of those parts of the system which are not illustrated in the drawings and their cooperation with the illustrated portions will be set forth in the following general description. After the general description a detailed analysis of the transmission of controls from the control office will be given.

GENERAL DESCRIPTION

15 The symbols (+) and (−) are employed to indicate the positive and negative terminals respectively of suitable batteries or other sources of direct current and the circuits with which these symbols are used always have current flowing in the same direction, that is, from (+) to (−) outside of the battery itself.

For convenience in describing the operation of the system the two line wires connecting the control office with the stations are identified by referring to them as the line and return conductors. These two conductors extend in series through all of the field stations and are normally connected together at the end station by means of back contact 200 of relay LO², illustrated in the upper right hand portion of Fig. 2B.

In considering the organization of the line circuit, it will be understood that additional field stations may be connected in series therewith, between the control office and the illustrated station or between the illustrated station and the end station. For convenience in describing the step-by-step operation of the system and the coding operations at the various steps, the impulse or energized periods of the line circuit will be referred to as the "on" periods and the space periods between impulses (deenergized periods of the line) will be referred to as the "off" periods.

Control office equipment.—The control office (Figs. 1A and 1B) includes a quick acting line relay F and a quick acting line repeater relay FP, the former repeating the impulses applied to the line circuit and the latter repeating the operations of relay F during a cycle of operations. Slow acting relays SA, SB and SC are picked up in sequence at the beginning of each cycle and are dropped out in sequence at the end of each cycle. Relay SA has such slow acting characteristics that it does not drop between successive "on" periods during a cycle, since these "on" periods follow each other at a sufficiently rapid rate to intermittently energize relay SA (by the intermittent operation of relay FP), so that it does not have time to drop between periods of its energization. Relay SB is a direct repeater of relay SA and relay SC is a direct repeater of relay SB, consequently these two relays remain picked up as long as relay SA is picked up.

65 The impulses of a cycle effect the step-by-step operation of the stepping relay bank, comprising stepping relays 1V, 2V, 3V, 4V and LV and a half-step relay VP. This stepping relay bank is arranged so that a separate stepping relay is picked up during each "off" period and the half-step relay shifts its position, alternately picking up and dropping, during each "on" period.

70 Impulse and impulse timing relays 1E, 2E and 3E are controlled by the stepping relay bank

in such a way that the impulses in the line circuit are made abnormally short or normally long as determined by whether or not code sending relay PF is picked up or not respectively at each step. Relays 1E, 2E and 3E also time the "off" periods by making them abnormally long or normally short as determined by whether or not code sending relay PB is picked up or not respectively at each step. An "off" period is made abnormally long by including the drop away times of relays PT and PB, as will be more specifically pointed out in the detailed description. An "on" period is made abnormally short by picking up relay PF and consequently opening the line without waiting for the 1E, 2E and 3E operations.

75 Polarity control relays PC and NC are for the purpose of applying (+) and (−) impulses respectively to the line circuit in accordance with selected codes. Code determining relay CD is one of a bank of such relays which are so interconnected that the momentary depression of a starting button STB picks up the associated start relay CH, which in turn picks up the associated relay CD for initiating the system and selecting the code to be applied during the resulting cycle. The interconnection of the CD and CH relays is such that the rapid successive operations of a plurality of starting buttons are stored, but only one CD relay is permitted to be picked up at any one time. Since this feature is immaterial to an understanding of the present invention it is not shown in detail, it having been completely disclosed in the prior application of N. D. Preston, et al., Ser. No. 455,304, filed May 24, 1930, corresponding to Australian Patent 1501 of 1931.

80 As typical of the control levers located in the control office, switch machine levers 1SML and 2SML are shown. These levers are for the purpose of governing track switches 1TS and 2TS as the illustrated field station, which field station is assumed to be selected when relay CD of Fig. 1A is picked up, as determined by the particular connection of code jumpers 10 and 11. It will be understood that additional levers for controlling the signals at the stations will be provided, but it is not believed necessary to complicate the drawings by showing this additional equipment, since the operations controlled by levers 1SML and 2SML are typical of the operations controlled by additional levers.

85 Cycle controlling relay C is picked up to initiate a control cycle, this relay remaining up during each control cycle and, although not illustrated, it prevents a field start condition being initiated, as well as controlling the energy for the polar control selection circuits as will be pointed out in detail.

90 A track diagram comprising miniature track switches 1ts and 2ts, corresponding to track switches 1TS and 2TS respectively at the field station, and an OS lamp OSL, are provided, but control of these miniature track switches and the OS lamp is omitted since no portion of indication transmission is included in the present disclosure.

95 *Field station equipment.*—The field station (Figs. 2A and 2B) includes a quick acting line relay F¹ of the biased to neutral polar type and it is assumed that the polar contacts of this relay are operated to the right when a (+) impulse is applied to the line conductor and to the left (normal condition as illustrated) when a (−) impulse is applied to the line conductor. Quick acting line repeating relay FP¹ repeats the im-

5 pulse in the line circuit irrespective of their polarities. Slow acting relays SA¹ and SB¹ correspond to similar relays in the control office and are used to define the bounds of an operating cycle, since they are picked up at the beginning of each cycle and are dropped at the end of each cycle.

10 A stepping relay bank, including relays 1V¹, 2V¹, 3V¹, 4V¹ and VP¹, is provided and which operates in synchronism with the corresponding relays of the control office stepping relay bank. Executing relay EX¹ is a last step relay corresponding to relay LV in the control office, but as will be described in detail it is for the purpose 15 of executing stored controls.

20 Track switches 1TS and 2TS are operated by switch machines 1SM¹ and 2SM¹ respectively in accordance with the switch controls transmitted over the line circuit, which selectively position 25 switch machine relays 1SMR¹ and 2SMR¹. Suitable signals are also provided (not shown) for governing traffic over the illustrated track section and their control is in accordance with suitable automatic signalling, in cooperation with 30 manual signalling controlled over the communication system. Since this signal control is accomplished at the various steps of the cycle in a manner similar to that shown for controlling the switch machine operation, it is believed unnecessary to illustrate this portion of the system.

35 Since indication transmission is not illustrated in the present disclosure, the usual track batteries and track relays and the usual switch machine repeating relays and the like are not shown at the illustrated field station.

40 Relays CF¹, CB¹, MF¹ and MB¹ illustrated in Fig. 2A are for the purpose of registering and storing the lengths of the "on" and "off" periods 45 in accordance with the codes which determine the lengths of these periods. The detailed operation of these relays will be explained later. During the transmission of polar controls for station selection the lengths of the "on" and "off" periods during these same steps are registered by relays such as ONS¹ and OFS¹ until the execution period after station selection, when the code stored on these storing relays is executed to the function control relays such as 1SMR¹ and 2SMR¹.

50 Station identification relay SO¹ and its co-operating stick relay SOS¹ are shown in Fig. 2A to illustrate the station selection feature, whereby controls are only transmitted to the function 55 control relays after the station selection portion of the cycle and only at one station, which one station has its relay corresponding to SO¹ picked up.

OPERATION

60 In the accompanying drawings the system is illustrated as being in its normal condition, from which it may be initiated for the transmission of controls by the operation of starting button STB (see Fig. 1A). The two-wire line circuit 65 is normally energized with negative potential applied to the line conductor so that line relay F in the control office is picked up and the polar line relays at the stations have their polar contacts positioned to the left. The normally energized line circuit provides means whereby the 70 system may be initiated from a field station for the transmission of indications (not shown in the present disclosure), by opening the normally energized line circuit for registering a field start 75 in the control office by dropping normally picked

up relay F, as shown, for example, in the British Patent No. 425,925 dated November 20, 1932.

5 A cycle of operations for the transmission of controls is started by quickly changing the negative line energization to a positive line energization, which registers in the control office and at the various field stations the condition that the following cycle is for the transmission of controls.

10 Normal condition.—The line circuit is normally energized over a circuit traced from the (+) terminal of line battery LB (Fig. 1A), back contact 12 of relay PC, front contact 13 of relay NC, return conductor 14, back contact 200 of relay LO² at the end station, line conductor 114, winding of relay F¹, line conductor 115, winding of relay F, conductor 15, back contacts 67, 66 and 65 of relays PF, PB and 1E respectively, front contact 64 of relay 2E, back contact 16 of relay 3E, front contact 17 of relay NC and back contact 20 18 of relay PC, to the (-) terminal of battery LB. This negative line energization actuates the line relays as above described.

20 Relay 2E in the control office is normally energized over an obvious circuit completed at back contact 19 of relay 1E. Relay PT in the control office is normally energized over an obvious circuit completed at back contact 20 of relay PB. Relay NC in the control office is normally energized over a circuit extending from (+), back contact 21 of relay C, back contact 22 of relay SC and winding of relay NC, to (-).

25 Relay MB¹ at the field station is normally energized over an obvious circuit completed at back contact 100 of relay CB¹. Relay CF¹ at the field station is normally energized over an obvious circuit completed at back contact 101 of relay FP¹. All other neutral relays are normally de-energized and it will be understood that the mag stick relays illustrated in Fig. 2B, have their contacts illustrated in their right hand positions, because of the construction of these relays whereby they maintain their contacts in their last operated positions after the associated relays are deenergized.

30 Manual start.—The operation of button STB for initiating a control cycle closes an obvious circuit for picking up relay CH. Relay CH closes a stick circuit for itself extending from (+), back contact 22 of relay CD, front contact 23 and winding of relay CH, to (-). Relay CD is picked up over a circuit extending from (+), back contact 24 of relay SB, back contact 25 of relay LS, front contact 26 of relay CH and lower winding of relay CD, to (-). Relay CD closes 35 a stick circuit for itself extending from (+), back contact 27 of relay LV, conductor 28, winding of relay LS, front contact 29 and upper winding of relay CD, to (-).

40 The opening of back contact 22 of relay CD deenergizes and drops relay CH. Relay LS is picked up over the stick circuit above described for relay CD and relay LS in turn opens the pick up circuits for other CD relays at back contact 25, so that other stored office start conditions, manifested by other CH relays being picked up, are ineffective to pick up the associated CD relays during this cycle of operations.

45 Relay C is picked up over a circuit extending from (+), back contact 24 of relay SB, front contact 25 of relay LS and winding of relay C, to (-). The picking up of relay C opens the above described normally energized circuit of relay NC at back contact 21, which releases relay NC. Relay PC is picked up over a circuit extending 50

from (+), front contact 21 of relay C, conductor 38, back contacts 31, 32, 33 and 34 of relays 4V, 3V, 2V and 1V respectively, conductor 35 and winding of relay PC, to (-).

5 The dropping of relay NC and the picking up of relay PC reverses the connection from battery LB to the line circuit, so that this line is now energized with a positive potential by way of pole changing contacts 12, 13, 17 and 18. This 10 quick reversal of current in the line circuit is effective to momentarily drop relay F, but this has no effect on the control office circuits because the cycle demarking relays SA, SB and SC are not yet picked up so that the operation of the 15 relay F is not repeated by the relay FP. Likewise the polar contacts of relay F¹ are shifted to the right and its effect on the field station circuits will be later described.

Relay FP in the control office is picked up 20 over a circuit extending from (+), front contact 36 of relay PC, conductor 36, front contact 37 of relay F and winding of relay FP, to (-). Relay SA is picked up over a circuit extending from (+), front contact 35 of relay PC, conductor 36, front contact 38 of relay FP, conductor 39 and winding of relay SA, to (-). Relay SA completes a stick circuit for relay C which includes front contacts 73 and 93.

Relay SB is picked up over an obvious circuit 30 completed at front contact 40 of relay SA and relay SC is picked up over an obvious circuit completed at front contact 24 of relay SB. The opening of back contact 22 of relay SC opens the above described normally energized circuit 35 for relay NC, so that this circuit will not be completed at the end of the cycle until relay SC is dropped.

Referring to the field station, relays SO¹ and SOS¹ are picked up over a circuit extending from 40 (+), back contact 102 of relay 1V¹, conductor 103, contact 104 of relay F in its right hand dotted position, conductor 105, back contacts 106, 107, 108 and 109 of relays 4V¹ 3V¹, 2V¹ and 1V¹ respectively, conductor 110 and upper windings 45 of relays SOS¹ and SO¹, to (-). Relay FP¹ is picked up over a circuit extending from (+), contact 111 of relay F¹ in its right hand dotted position, front contact 112 of relay SO¹ and winding of relay FP¹, to (-). Relay SA¹ is picked up over an obvious circuit completed at front contact 113 of relay FP¹ and relay SB¹ is picked up over an obvious circuit completed at front contact 116 of relay SA¹.

The above operations effect the conditioning 55 of the control office and field station circuits so that the following impulses are effective to operate the stepping relay banks in synchronism. It will be understood that the same operations as described in connection with the illustrated field 60 station, take place at other field stations connected to the line circuit.

Line impulsing and stepping relay operations.—Although the description of the impulsing and stepping operations will be more particularly directed to Figs. 1A and 1B, it will be understood that similar stepping operations take place at the field station illustrated in Figs. 2A and 2B and at other stations along the line. Contacts 141 and 142 of relay FP¹ correspond 65 to contacts 41 and 42 of relay FP in the office and the dotted line associating contacts 141 and 142 with the field station stepping relay bank indicates that this bank of stepping relays is controlled in the same manner that the stepping relay bank in the control office is controlled by 70 75

contacts 41 and 42. Therefore it is believed unnecessary to illustrate or describe the operation of the field station stepping relay bank in detail.

Relay VP is picked up in response to the picking up of relay SC over a circuit extending from (+), front contact 43 of relay SC, conductor 44, front contact 41 of relay FP, back contact 45 of relay 1V and winding of relay VP, to (-). A first stick circuit for relay VP is completed which extends from (+), on conductor 44, front contact 46 of relay VP, back contact 45 of relay 1V and winding of relay VP, to (-).

Relay 1E is now picked up over a circuit extending from (+), front contact 47 of relay SC, conductor 36, back contacts 48, 49, 50 and 51 of 15 relays 4V, 3V, 2V and 1V respectively, front contact 52 of relay VP, conductor 53 and winding of relay 1E, to (-). The picking up of relay 1E deenergizes relay 2E at back contact 19 and relay 2E drops after a period of time determined by 20 its slow acting characteristics. The dropping of relay 2E closes an obvious circuit for picking up relay 3E at back contact 54.

The picking up of relay 3E marks the end of the conditioning period and the beginning of the 25 first "off" period, by deenergizing the line circuit at open back contact 16. The deenergization of the line effects the dropping of relays F and F¹ and because of open front contact 37 of relay F and open polar contact 111 of relay F¹, 30 relays FP and FP¹ are dropped.

A second stick circuit is now closed for relay VP extending from (+), front contact 43 of relay SC, conductor 44, back contact 41 of relay FP, front contact 55 and winding of relay VP, 35 to (-). Relay 1V is now picked up over a circuit extending from (+) on conductor 44, back contact 42 of relay FP, front contact 56 of relay VP, back contacts 57 and 58 of relays 4V and 2V respectively and winding of relay 1V, to (-). 40 Relay 1V closes an obvious stick circuit for itself at its front contact 59. During the following operation, when relays 2V, 3V, 4V and 1V are picked up in sequence, similar stick circuits are closed at their front contacts 60, 61, 62 and 63 45 respectively.

The picking up of relay 1V deenergizes relay 1E because the above described energizing circuit for this relay is now open at back contact 51. The dropping of relay 1E effects the picking up of relay 2E because of closed back contact 19 and the picking up of relay 2E effects the dropping of relay 3E because of open back contact 54.

This marks the end of the first "off" period 55 and the beginning of the first "on" period by again energizing the line circuit at back contact 16 of relay 3E, completed through front contact 64 of relay 2E and back contacts 65, 66 and 67 of relays 1E, PB and PF respectively. The energization of the line circuit effects the picking up of relays F, F¹, FP and FP¹ over the previously 60 described circuits. Relay VP is now dropped because its first stick circuit is open at back contact 45 of relay 1V and its second stick circuit is 65 open at back contact 41 of relay FP. The dropping of relay VP again completes the pick up circuit for relay 1E, previously described but now extending through back contact 52 of relay VP and front contact 51 of relay 1V. The picking 70 up of relay 1E and the consequent opening of its back contact 19 drops relay 2E and the closure of its back contact 54 picks up relay 3E.

This marks the end of the first "on" period 75 and the beginning of the second "off" period by

deenergizing the line circuit at open back contact 16. Relays F, FP, F¹ and FP¹ are released as before and relay 2V is picked up over a circuit extending from (+) on conductor 44, back contact 42 of relay FP, back contact 56 of relay VP, back contact 68 of relay 3V, front contact 69 of relay 1V and winding of relay 2V to (-). The picking up of relay 2V deenergizes relay 1E by opening the circuit at back contact 50. The dropping of relay 1E again picks up relay 2E by way of back contact 19 and the picking up of relay 2E deenergizes relay 3E because of open back contact 54.

This marks the end of the second "off" period and the beginning of the second "on" period by again energizing the line, which again picks up relays F, FP, F¹ and FP¹. Relay VP is now picked up over a circuit extending from (+), on conductor 44, front contact 41 of relay FP, back contact 70 of relay 3V, front contact 71 of relay 2V and winding of relay VP, to (-). Relay VP again closes its first stick circuit as previously described and relay 1E is picked up by means of the circuit completed at front contact 52 of relay VP and front contact 50 of relay 2V. Relay 2E is now released because of open back contact 19 and relay 3E is picked up because of closed back contact 54.

This marks the end of the second "on" period and the beginning of the third "off" period by again deenergizing the line circuit, which in turn drops relays F, FP, F¹ and FP¹. The second stick circuit for relay VP is again completed and relay 3V is picked up over a circuit extending from (+) on conductor 44, back contact 42 of relay FP, front contact 56 of relay VP, back contact 57 of relay 4V, front contact 58 of relay 2V and winding of relay 3V, to (-). Relay 1E is now released because of open back contact 49 of relay 3V, relay 2E is now picked up because of closed back contact 19 of relay 1E and relay 3E is now dropped because of open back contact 54 of relay 2E.

This marks the end of the third "off" period and the beginning of the third "on" period by again energizing the line circuit, which in turn picks up relays F, FP, F¹ and FP¹. Relay VP is again released because its first stick circuit is open at back contact 70 of relay 3V, and its second stick circuit is open at back contact 41 of relay FP. Relay 1E is again picked up because its circuit is now complete at back contact 52 of relay VP and front contact 49 of relay 3V. Relay 2E is released and relay 3E is picked up because of open back contact 19 and closed back contact 54 respectively.

This marks the end of the third "on" period and the beginning of the fourth "off" period by again deenergizing the line circuit, which in turn drops relays F, FP, F¹ and FP¹. Relay 4V is now picked up over a circuit extending from (+) on conductor 44, back contact 42 of relay FP, back contact 56 of relay VP, front contact 68 of relay 3V and winding of relay 4V, to (-). Relay 1E is now released because of open back contact 48 of relay 4V, relay 2E is picked up because of closed back contact 19 of relay 1E and relay 3E is released because of open back contact 54 of relay 2E.

This marks the end of the fourth "off" period and the beginning of the fourth "on" period by again energizing the line circuit, which is effective to pick up relays F, FP, F¹ and FP¹. Relay VP is now picked up over a circuit extending from (+) on conductor 44, front contact 41 of relay

FP, front contact 72 of relay 4V and winding of relay VP to (-). The first stick circuit for relay VP is again closed and relay 1E is picked up because its circuit is completed at front contact 52 of relay VP and front contact 48 of relay 4V. Relay 2E is released because of open back contact 19 and relay 3E is picked up because of closed back contact 54.

This marks the end of the fourth "on" period and the beginning of the clearing out "off" period by deenergizing the line circuit, which in turn drops relays F, FP, F¹ and FP¹. Relay LV is now picked up over a circuit extending from (+) on conductor 44, back contact 42 of relay FP, front contact 56 of relay VP, front contact 57 of relay 4V and winding of relay LV, to (-). The picking up of relay LV effects the release of relays CD and LS because of open back contact 27 of relay LV.

The circuit for relay 1E is not controlled by relay LV, as it was with the previous stepping relays, therefore relay 1E is not dropped during this "off" period to cause the picking up of relay 2E and the dropping of relay 3E for again energizing the line. This makes the clearing out "off" period extremely long and, because relay FP remains down, the energizing circuit for relay SA is held open for an extremely long period at open front contact 38, which allows relay SA to drop. The dropping of relay SA and the consequent opening of its front contact 40 releases relay SB and the opening of its front contact 24 releases relay SC. Relay SC removes energy from the stick circuits of the stepping and half-step relays at open front contact 43, so that these relays are released.

Relay 1E is also released because of open front contact 47 of relay SC, relay PC being down at this time with its front contact 35 open. The dropping of relay 1E picks up relay 2E because of closed back contact 19 and the picking up of relay 2E drops relay 3E because of open back contact 54.

This marks the end of the clearing out "off" period and the beginning of the normal "on" period by again normally energizing the line. This energization is negative because relay C was dropped during the clearing out "off" period, by the opening of its stick circuit at front contact 13 of relay SA and the dropping of relay C effected the release of relay PC or NC (which ever was picked up by the last code), by the opening of front contact 21. Relay NC is picked up when relay SC drops to close its back contact 22, which again completes the normal energizing circuit for relay NC. This negative energization of the line again picks up relay F and positions the polar contacts of relay F¹ to the left, which is the normal condition of the system.

As above mentioned, the field station steps through the cycle in a manner similar to that described for the office. Relay EX¹, however, is picked up during the clearing out "off" period at the same time that relay LV picks up and by means of a similar circuit. Relay SA¹ is dropped during the clearing out period because of open front contact 113 of relay FP¹ and relay SB¹ is dropped because of open front contact 116 of relay SA¹. The stepping and half-step relays are deenergized in a manner similar to the deenergization of these relays in the control office. Assuming that the station illustrated is the one selected during this cycle, relay SO¹ will remain picked up throughout the cycle until the clearing out period, when it will be released by deenergizing its stick circuit at open front contact 117 of

relay SB¹. The SOS¹ relay will be selectively operated and the SO¹ relay will be maintained operated in a manner which will be described in connection with station selection.

5 *Polarity selection of control impulses.*—It has been described how the normal negative energization of the line circuit is changed to a positive energization for conditioning the office and field station circuits in response to the initiation of a 10 control cycle.

10 It will now be assumed that the system steps through the cycle as previously described and an explanation will be given of how the polarity of each control impulse is determined.

15 Code jumper No. 11 in its illustrated position makes the first impulse (first "on" period) positive. This is because relay PC is energized during the preceding (first) "off" period when relay 1V picks up. In other words, the switching 20 of contact 34 of relay 1V from its back to its front point switches the (+) on conductor 30 from conductor 35, by way of conductor 74, front contact 75 of relay CD, jumper 11, PC bus and winding of relay PC, to (-). With relay PC up and 25 relay NC down, the line is energized with a positive impulse by way of pole changing contacts 12, 13, 17 and 18 and over the circuit including the line and return conductors as previously described.

30 In the event that jumper 11 is connected in its alternate dotted line position, then relay NC would be picked up and relay PC would be down, which would result in applying a negative impulse to the line circuit.

35 When relay 2V is picked up during the second "off" period, the polarity of the second impulse is determined by the connection of code jumper 10 and as illustrated in Fig. 1A, relay NC will be picked up over a circuit extending from (+), 40 front contact 21 of relay C, conductor 30, back contacts 31 and 32 of relays 4V and 3V respectively, front contact 33 of relay 2V, conductor 76, front contact 77 of relay CD, jumper 10, NC bus and winding of relay NC, to (-).

45 In the event that jumper 10 is in its alternate dotted line position, then relay PC would be picked up during the second "off" period for making the second impulse positive instead of negative. Although only two code jumpers are 50 shown, it is believed that the typical example illustrated and described is sufficient to indicate how the selection may be made on additional steps of the cycle, for rendering the impulses in the line circuit positive or negative, as determined 55 by the code jumper connections selected by the particular CD relay which is picked up. These polar impulses are determined for the third and fourth steps (when these steps are used for applying polar impulses to the line), by selections 60 No. 3 and No. 4 made at front contacts 32 and 31 of relays 3V and 4V respectively.

65 It will also be understood that, in the event of the station selection impulses being controlled on the first two steps of the cycle as indicated in the drawings, function control impulses on additional steps of the cycle can be made positive or negative, by extending the No. 3, No. 4 and the like channel circuits through front contacts of relay CD to control levers, which determine the 70 polarity of these impulses in their normal and reverse positions, in the same way that they are determined by the two connections of the code jumpers. In the present disclosure, however, it is assumed that station selection is effected by 75 the polarity of the first two control impulses.

From the above it will be apparent that different polar code combinations, comprising a choice of two per step may be used for selecting field stations and for controlling devices at the selected station.

5 *Timing of control impulses.*—The timing of the control impulses applied to the line circuit is illustrated as being determined by the positions of levers 1SML and 2SML of Fig. 1A, but it will be apparent from the previous description, as 10 well as the description which follows, that the timing of the impulses may be effective to provide station selection codes, since a choice of two is provided for each "on" period and another choice of two for each "off" period.

15 In the previous description of the stepping operations it was assumed that each "off" period was normally short. This because relay PB or Fig. 1A remains down, so that the line is closed to mark the end of each "off" period by the dropping of 20 relay 3E and the consequent closing of its back contact 66. With levers 1SML and 2SML in their illustrated positions no energy is applied to the channel circuits to which they are connected for 25 picking up relay PE, thus the "off" periods coded by these two levers are normally short.

To illustrate how an "off" period may be abnormally long it will be assumed that lever 1SML is in its reverse position. When relay 1V picks up during the first "off" period a circuit is closed for 30 picking up relay PB which extends from (+), lever 1SML in its left hand dotted position, front contact 78 of relay CD, conductor 79, front contact 80 of relay 1V, back contact 81 of relay 2V, front contact 82 of relay VP, back contact 83 of 35 relay FP, conductor 84, front contact 85 of relay PT and winding of relay PB, to (-). The picking up of relay PB opens the line at another point, that is, back contact 66 of this relay so that the closure of back contact 66 is ineffective to energize the line, since front contact 9 of relay F is open at this time.

40 Relay PB remains picked up and the line remains open until slow acting relay PT drops and, by opening the circuit of relay PB at front contact 85, relay PB drops and closes up the line. Due to the time interval introduced by the release time of relays PT and PB, the "off" period is made abnormally long.

45 It will be observed that the dropping of relay 50 PB again picks up relay PT because of closed back contact 20 and that the closure of front contact 85 again picks up relay PB. This line is not opened by the opening of back contact 66 this time, because relay F is up which closes a bridge 55 path around contact 66 at front contact 9.

In the previous description the "on" periods were normally long because relay PF was not picked up, thus the end of each "on" period was not marked until relay 3E picked up, which, because of the time interval introduced by the slow 60 dropping of relay 2E during each "on" period, results in these "on" periods being normally long.

To illustrate how an "on" period is made abnormally short, it will be assumed that lever 2SML 65 is in its reverse position. With relay 1V picked up, a circuit is closed for picking up relay PF during the first "on" period, when relay VP drops, which circuit extends from (+), contact of lever 2SML in its reverse position, front contact 86 of relay 70 CD, conductor 87, front contact 88 of relay 1V, back contact 89 of relay 2V, back contact 90 of relay VP, front contact 91 of relay FP, conductor 92 and winding of relay PF, to (-).

75 The picking up of relay PF, immediately after

the shifting of the VP relay, opens up the line circuit at back contact 67 without waiting for relay 1E to pick up, relay 2E to drop and relay 3E to pick up for opening the line as previously described. This quick opening of the line circuit terminates the "on" period very shortly after the shift of the VP relay, which makes the "on" period comparatively short.

From the above examples it is believed apparent that any of the four "off" and "on" periods of the previously described cycle can be made short or long for coding the control impulses, either for station selection or for the transmission of controls to the selected station, as determined by the separate channel circuit selections made as illustrated in Fig. 1B, having the legends "off controls short or long" and "on controls short or long" applied thereto.

Station selection and transmission of controls.—It was previously described how relays SO¹ and SOS¹ were picked up at the start of the cycle. With the first impulse (+) as determined by jumper 11 and the second impulse (—) as determined by jumper 10, relay F¹ is positioned to the right during the first "on" period and to the left during the second "on" period. The picking up of relay SB¹ during the conditioning "on" period establishes a stick circuit for relay SOS¹ extending from (+), front contact 117 of relay SB¹, front contact 118 of relay FP¹, front contact 119 and lower winding of relay SOS¹, to (—). A stick circuit is also closed for relay SO¹ extending from (+), front contact 117 of relay SB¹, front contact 120 of relay SOS¹, front contact 121 and lower winding of relay SO¹, to (—).

The dropping of relay FP¹ during the first "off" period drops relay SOS¹ by opening the above described stick circuit at front contact 118. At the same time that this stick circuit is opened, and before relay SOS¹ drops, another stick circuit is closed for relay SO¹ extending from (+), front contact 117 of relay SB¹, back contact 118 of relay FP¹, front contact 121 and lower winding of relay SO¹, to (—).

During the first "on" period the actuation of the polar contacts of relay F¹ to the right completes a pick up circuit for relay SOS¹ extending from (+), front contact 122 of relay SO¹, contact 104 of relay F¹ in its right hand dotted position, conductor 105, back contacts 106, 107 and 108 of relays 4V¹, 3V¹ and 2V¹ respectively, front contact 109 of relay 1V¹, code jumper 123 in its full line position, conductor 110 and upper windings of relays SOS¹ and SO¹, to (—). It will be observed that this pick up circuit for relay SOS¹ is dependent on relay SO¹ being picked up, this because relay 1V¹ has its back contact 102 open.

It will also be observed that this pick up circuit for relay SOS¹ comprises an energizing and holding circuit for relay SO¹, before relay FP¹ drops and breaks the stick circuit for relay SOS¹ at front contact 118. Therefore, if the code jumper 123 is in its alternate dotted line position, relay SOS¹ cannot be picked up and the stick circuit for relay SO¹ by way of front contact 120 of relay SOS¹ is incomplete, so that the continued energization of relay SO¹ is made dependent on this selecting circuit including jumper 123. If this selecting circuit is incomplete and relay SOS¹ is not picked up, then when relay FP¹ opens its back contact 118 the stick circuit including this back contact for relay SO¹ is broken and this latter relay is dropped out.

In the example assumed, jumper 123 in its full line position maintains relay SO¹ picked up and

allows relay SOS¹ to be picked up, after which the stick circuit for relay SO¹ is completed through front contacts 120 and 121 and the stick circuit for relay SOS¹ is completed through front contacts 118 and 119. This illustrates how the selection is made during the first "on" period and it will now be pointed out how relay SO¹ continues to be energized in response to the negative code applied to the line circuit during the second "on" period.

During the second "off" period, relay SO¹ is stuck up because of the closure of back contact 118 of relay FP¹ and relay SOS¹ is dropped out because of open front contact 118. Relay 2V¹ is picked up during the second "off" period and with relay F¹ actuated to the left the above described circuit through the upper windings of the SOS¹ and SO¹ relays is complete and may be traced from (+), front contact 122 of relay SO¹, contact 104 of relay F¹ in its left hand position, conductor 124, back contacts 125 and 126 of relays 4V¹ and 3V¹ respectively, front contact 127 of relay 2V¹, jumper 128 in its full line position and conductor 110 to the upper windings of the SO¹ and SOS¹ relays. Relay SOS¹ is picked up and stuck up and relay SO¹ is stuck up as previously described. It will be obvious that, with jumper 128 in its alternate dotted line position, a positive impulse is required for the second "on" period to complete the above described circuit.

With the station selection made on the first two steps, then a permanent stick circuit (complete throughout the cycle) is completed during the next "off" period when relay 3V¹ picks up, which stick circuit extends from (+), front contact 117 of relay SB¹, conductor 129, front contact 130 of relay 3V¹, back contact 131 of relay EX¹, conductor 132, front contact 121 and lower winding of relay SO¹, to (—).

Since the polar impulses of the first two steps are used for station selection, it becomes necessary to store the code comprising the short and long "off" and "on" periods of these two steps, so that these codes may be executed to the function control relays after the station is selected and only at the selected station.

Lever 1SML in its normal position determines that the first "off" period will be normally short as previously described. This means that relay FP¹ at the station will be picked up for again energizing relay CB¹ at front contact 101, before this relay had time to drop after its deenergization at open front contact 101. It will be obvious of course that relay CB¹ is picked up during each "on" period and is only dropped out during the succeeding "off" period when this "off" period is abnormally long.

The picking up of relay CB¹ during the previous "on" period opens the pick up circuit of relay MB¹ at back contact 100, but relay MB¹ is stuck up over a circuit including front contacts 133 and 134 of relays FP¹ and MB¹ respectively. During the short "off" period, both the pick up and stick circuits of relay MB¹ remain open at contacts 133 and 100 so that this relay drops and, since relay CB¹ does not drop out, relay MB¹ remains down. Then during the succeeding "on" period the condition of relay MB¹ is transferred by completing a circuit for the lower winding of relay OFS¹ which may be traced from (+), front contact 135 of relay SB¹, front contact 136 of relay SO¹, front contact 137 of relay FP¹, back contact 138 of relay MB¹, conductor 139, back contacts 143, 144 and 145 of relays 4V¹, 3V¹ and 2V¹ respec-

tively, front contact 146 of relay 1V¹ and lower winding of relay OFS¹, to (—).

Since relay OFS¹ is of the mag stick type the energization of its lower winding positions its 5 polar contacts to the right and they stay there until the end of the cycle. During the executing period switch control relay 1SMR¹ is energized to position its polar contacts to the right by means of a circuit extending from (+), back contact 147 10 of relay SA¹, front contact 148 of relay SB¹, front contact 149 of relay SO¹, conductor 140, front contact 150 of relay EX¹, contact 151 of relay OFS¹ in its right hand position and upper winding of relay 1SMR¹, to (—). Polar contact 152 15 of relay 1SMR¹ in its right hand position, controls the operation of switch machine 1SM¹ to its normal position.

In the event that lever 1SM¹ is in its reverse position, then the first "off" period would be about 20 normally long allowing relay CB¹ to drop out during this "off" period for picking up relay MB¹ by way of back contact 100, after the stick circuit of relay MB¹ is broken at front contact 133 of relay FP¹. During the next succeeding "on" 25 period the stick circuit for relay MB¹ is completed at front contact 133 before relay CB¹ is again picked up. This condition is transferred during the above mentioned succeeding "on" period by completing a circuit extending from 30 (+) at front contact 135 of relay SB¹, and extending through front contact 138 of relay MB¹, conductor 153, back contacts 154, 155 and 156 of relays 4V¹, 3V¹ and 2V¹ respectively, front contact 157 of relay 1V¹ and upper winding of relay OFS¹, to (—). The energization of the upper 35 winding of this relay positions its polar contacts to the left for energizing the lower winding of relay 1SMR¹ during the executing period, which positions its polar contacts to the left for operating switch machine 1SM¹ to its reverse position. 40

With lever 2SML in its normal position the first "on" period is normally long as already described. Because relay FP¹ remains picked up 45 with its back contact 101 open for a comparatively long interval, relay CF¹ drops and closes a circuit for picking up relay MF¹ extending from (+), back contact 158 of relay CF¹ and winding of relay MF¹ to (—). During the next succeeding 50 "off" period the dropping of relay FP¹ completes a stick circuit for relay MF¹ by way of front contact 159 of relay MF¹, before its pick up circuit is opened by the picking up of relay CF¹.

This condition is transferred during the above 55 mentioned succeeding "off" period by energizing the upper winding of relay ONS¹ over a circuit extending from (+), front contact 135 of relay SB¹, front contact 136 of relay SO¹, back contact 137 of relay FP¹, front contact 160 of relay MF¹, conductor 161, back contacts 162, 163 and 164 of 60 relays 4V¹, 3V¹ and 2V¹ respectively, front contact 165 of relay 1V¹ and upper winding of relay ONS¹, to (—). Polar contact 166 of relay ONS¹ is positioned to the right and an executing circuit 65 is closed at the end of the cycle for energizing the lower winding of relay 2SMR¹ by way of contact 166 in its right hand position. Polar contact 167 of relay 2SMR¹ controls the operation of switch machine 2SM¹ to its normal position.

With lever 2SML in its reverse position, the first 70 "on" period is made abnormally short and relay CF¹ does not have time to drop before relay FP¹ closes its back contact 101 and reenergizes this relay. Relay MF¹ is released (if up) by the opening of its stick circuit at back contact 133 and is 75 not again picked up because its pick up circuit

is open at back contact 158. During the succeeding "off" period the lower winding of relay ONS¹ is energized over a circuit extending through back contact 160 of relay MF¹, conductor 168, back contacts 169, 170 and 171 of relays 4V¹, 3V¹ and 2V¹ respectively, front contact 172 of relay 1V¹ and lower winding of relay ONS¹, to (—).

Relay ONS¹ operates its polar contacts to the left and during the execution period a circuit is 10 completed through contact 166 in its left hand dotted position for energizing the upper winding of relay 2SMR¹, which positions polar contact 167 to the left for operating switch machine 2SM¹ to its reverse position.

It is believed that the above examples are sufficient to indicate how the various code combinations are provided at any number of steps, as determined by the capacity of the system to which the present invention is applied. It will be understood that, when a station is dropped out during the station selection portion of a cycle by the dropping of its associated SO relay, stepping does not take place at such station because the associated FP relay has its circuit maintained open 20 at a front contact such as front contact 112 of relay SO¹. It will furthermore be observed that relay FP¹ is not energized during the normal condition of the system, because contact 111 of relay F¹ in its left hand position leads to open contact 173 of relay SB¹, but during the cycle front contact 173 is closed, so that relay FP¹ is operated irrespective of the position of polar contact 111 of relay F¹, as long as front contact 112 remains closed.

Having thus described one specific embodiment 35 of a centralized traffic controlling system, it is desired to be understood that the particular arrangements illustrated and suggested are only typical of applicant's invention and are not intended to indicate the exact circuit design and specific arrangement of parts necessary to carry out the features of the invention. This particular form has been chosen to facilitate in the disclosure rather than to limit the number of forms 40 which the invention may assume and it is furthermore to be understood that various modifications may be made in order to meet the various problems encountered in practice, the system may be varied in the number of field stations and the amount of apparatus at each field station may 45 be varied to suit local conditions, and any desired organization for the registration of a field station in the control office and the transmission of indications therefrom may be provided, all without 50 in any manner departing from the spirit or scope 55 of the present invention except as limited by the appended claims.

What I claim is:

1. In a remote control system; a line circuit; a source of current connected to said line circuit; 60 a polar line relay included in said line circuit; an impulse relay controlled by said line relay; means for at times opening and closing said line circuit and reversibly connecting said source of current thereto for producing a series of time 65 spaced polar impulses having polar characters in accordance with different codes, said line relay being intermittently operated by said time spaced impulses dependent upon their polarity and said impulse relay being operated irrespec- 70 tive of their polarity; means for prolonging selected ones of said impulses and time spaces of said series; two slow release relays each having a release time less than said prolonged impulses and time spaces and greater than impulses and 75

time spaces not prolonged; a pick up circuit for a first one of said slow release relays controlled by a back contact of said impulse relay; a pick up circuit for a second one of said slow release relays controlled by a front contact of said impulse relay; a plurality of devices; a first register means selectively controlled by the polarity of said series of time spaced impulses so as to be rendered active only in response to a particular one of said different codes; a second register means selectively positioned by said first slow relay during said impulses of said series in accordance with lengths of such impulses; a third register means selectively positioned by said second slow relay during time spaces between impulses of said series in accordance with the length of such spaces; and means for selectively controlling said plurality of devices at the end of said time spaced impulses in accordance with said second and said third register means only if said first register means is rendered active.

2. In a remote control system, control office and a field station connected by a single line circuit, transmitting means in said office for transmitting a series of time spaced positive and negative impulses over said line circuit, said impulses and said time spaces of said series all being selectively varied in length in accordance with controls to be transmitted and the polarity of the same impulses of said series being selected in accordance with a predetermined code pattern, step-by-step means at said station for operating through a cycle of operation in response to said impulses, means at said station for registering the length of the impulse and the length of the time space for each step, selecting means at said station distinctively conditioned only providing the polarity of said impulses for several steps conforms to a particular code pattern, a plurality 40 of electro-responsive devices at said station, and means for controlling said electro-responsive devices at the end of an operating cycle in accordance with the registered lengths of said impulses and time spaces only providing said selecting means has been distinctively conditioned, whereby the reception of controls and distinctive conditioning in accordance with a code can be simultaneously accomplished.

3. In a remote control system, a control office and a plurality of field stations connected by a single line circuit, means at said office for transmitting a series of time spaced positive or negative impulses over said line circuit, means at said office for varying the lengths of said impulses and the time spaces between such impulses in accordance with the controls to be transmitted to a particular station, said means also acting to determine the positive or negative polarity of the impulses in accordance with a code pattern assigned to that station, means at each of said stations for registering the lengths of the impulses and the lengths of the time spaces between said impulses, selecting means at each of said stations distinctively conditioned only provided said impulses conform in polarity to the code pattern assigned to that station, a plurality of electro-responsive means at each station, and means at each station for controlling said electro-responsive means at that station in accordance with the registered lengths of the impulses and time spaces at the end of said series of impulses only provided the selecting means at that station has been distinctively conditioned during such series of impulses by their positive and negative character-

istics conforming to the code call for that station.

4. In a remote control system; a control office and a plurality of field stations connected by a line circuit; transmitting means at said control office for transmitting different series of time spaced current impulses of selected polarities over said line circuit, the polarities of any given series being dependent upon the particular station to be selected for the reception of controls during that series of impulses; means at said control office acting on said transmitting means during any given series for varying the lengths of said impulses and the time spaces between such impulses of that given series in accordance with the controls for the field station to be selected for that series; storing means at each of said field stations for receiving and distinctively registering, only when rendered effective, the lengths of the impulses and the lengths of the time spaces between the impulses of any series; station selecting means at each of said field stations responsive only to the polarity of the impulses of a particular one of said different series for rendering effective said storing means at that station; a plurality of power-operated devices at each of said field stations; and means at each of said field stations dependent upon the response of said station selecting means at that station to its particular one of said different series for distinctively operating the power-operated devices at that station in accordance with the lengths of the impulses and the lengths of the time spaces for that series as registered in said storing means.

5. In a remote control system; a control office and a field station connected by a line circuit; transmitting means at said control office for transmitting a plurality of time spaced current impulses over said line circuit; means at said office for acting on said transmitting means to vary the polarity of said plurality of impulses, the lengths of said plurality of impulses, and the time spaces between said plurality of impulses; receiving means at said station responsive to said plurality of impulses on said line circuit and acting to store the lengths of said impulses and the time spaces between such impulses when such receiving means is rendered effective; selecting means controlled by the polarity of said plurality of impulses for rendering said receiving means effective; a plurality of devices at the field station; and means acting only after all of said plurality of impulses have been received and their polar characteristics have controlled said selecting means for distinctively and simultaneously controlling said devices in accordance with the lengths of said plurality of impulses and the lengths of said time spaces between such impulses as stored in said receiving means.

6. In a remote control system; a control office and a plurality of field stations connected by a single line circuit; a source of direct current energy in said control office; transmitting means at said control office alone for timing and impressing series of time spaced impulses of selected polarities on said line circuit from said source of energy; means at the control office acting on said transmitting means to determine the relative short and long lengths of said impulses and the relative short and long lengths of the spaces between such impulses of any given series in accordance with the controls to be transmitted to the particular station selected for that series, said means also acting to determine the positive and negative polarities of said impulses in accordance

with the code assigned to that particular station; station selecting means at each of said field stations rendered active at the beginning of every series but maintained active during any given series only if the polarities of the impulses of that series conform to the code assigned that field station; storing means at each field station for registering the lengths of the impulses and the lengths of the spaces between said impulses of any given series only so long as said station selecting means is active during said series; a plurality of devices at each of said field stations; and means at each of said field stations for controlling said devices at that station in accordance with the condition of said storing means at the end of any given series only if said station selecting means has been maintained active throughout said series.

7. In a remote control system; a control office and a plurality of field stations connected by a single line circuit; a plurality of devices at each of the several field stations, a plurality of control levers in the control office for each of said field stations; transmitting means at said control office alone for timing and impressing series of time spaced impulses of selected polarities on said line circuit from said source of energy; a plurality of code determining relays in the control office respectively associated with the several field stations and effective, when rendered active, to cause said transmitting means during a particular series of impulses to be controlled in accordance with the control levers for that associated field

station to determine the relative short and long lengths of said impulses and the relative short and long lengths of the spaces between such impulses of any given series for the particular station with which such levers are associated, said code determining relay for any particular station also acting to determine the positive and negative polarities of said impulses for the series in accordance with the code assigned to that particular station; means associated with said code determining relays for allowing only one of the several code determining relays to be active during the same series of time spaced impulses; station selecting means at each of said field stations rendered active at the beginning of every series of impulses but maintained active during any particular series only if the polarities of the impulses of that series conform to the code assigned to its field station; storing means at each field station for registering the lengths of the impulses of any series and the lengths of the spaces between the impulses of any series only so long as said station selecting means is active during said series; and means at each of said field stations for controlling said devices at that station in accordance with the condition of said storing means at the end of any given series providing said station selecting means has been maintained active throughout the series by reason of the polarity of the impulses of such series conforming to the code call of that station.

FREDERICK W. BRIXNER.
